UNITED STATES PATENT OFFICE

2,638,766

AUTOMATIC WASHING MACHINE CONTROL

John H. Palmer, Milford, Conn., assignor to General Electric Company, a corporation of New York

Application April 21, 1951, Serial No. 222,223

4 Claims. (Cl. 68—12)

1

This invention relates to controls for a sequence of operations and, more particularly, to mechanisms for controlling a fixed series of operations of automatic washing machines.

Many well-known automatic washing machines employ an outer tub having mounted therein a basket in which clothes may be washed, rinsed, and centrifugally dried. This basket may be imperforate, except for a row of overflow ports arranged around the upper wall through which overflow wash water may flow during filling and through which water is discharged during centrifugal extraction. Such machines are customarily provided with an oscillatable washing mechanism, such as a bladed agitator, mounted within the basket. Mechanism is provided of several well-known types for alternately oscillating the washing means for washing or rinsing and rotating the basket for centrifugally drying the clothes. Frequently, float switches, or other water-level responsive means, are provided in the bottom of the outer tub as a means of controlling electro-responsive water inlet valves, and a pump or other drain means is commonly used for exhausting the water collected in this tub.

Such clothes washing machines are usually provided with one of several similar types of timer motor driven program controllers for effecting a predetermined series of operations including oscillation of the washing means, rotation of the clothes basket, a pause between each oscillating and rotating operation, and a final pause following the last active operation. With washing machines using these well-known control mechanisms, it has been necessary for the operator, when desiring to stop the machine quickly, to move the control knob to position the indicator within the small space marked "off" on the control dial. Although most control mechanisms have been provided with manual means for turning the control both in the same direction that it is driven and in the opposite direction, the operator has frequently found it difficult to locate the correct "off" position in an emergency, especially during a spinning operation, since heavy baskets may coast at a high rate of speed, making it difficult to tell whether or not the power supply has been interrupted.

In addition to the difficulty in finding the "off" position in an emergency, there have been problems encountered in manually changing the position of the control dial to vary the duration of, eliminate, or repeat an operation. The problems arise primarily because of the difficulty in determining when an operation begins or ends.

For example, during spinning the dial may be turned back to lengthen the extraction time and if turned too far the control will cause opening of the water inlet valves, admitting water to the basket, which, while the basket continues to coast at high speed, is thrown into the outer tub, prematurely operating the float switch. This could be the cause of a dry agitate operation, which might tear the clothes. The problem is particularly serious in the case of automatic washing machines in which no brake or other means is provided to stop rotation of the spin basket, which instead is permitted to coast to a stop. In such machines, moreover, when the user accidentally turns the control dial during spinning to a position in which the control calls for water fill, the clothes, because of the high coasting speed of the basket, will be moving at such a rapid rate that their mere impact with the incoming water will cause fraying and possibly tearing. In addition, it is possible that the control dial may be turned to a position calling for oscillation of the clothes-washing means and, if this occurs while the spin basket is rapidly rotating, it could cause damage to the transmission mechanism. With machines in which the shift from oscillation of the washing means to rotation of the spin basket is made in response to a reversal of the direction of motor rotation, there would not be time for the spinning basket to slow down sufficiently to cut in its start winding and, consequently, reversal of the winding connections would have no effect and the basket would continue to be rotated by the motor during any suddenly initiated wash or rinse period.

It would be a simple matter to remedy these difficulties by the provision of a control mechanism which cannot be turned manually after the beginning of the operational sequence, and a separate "on-off" switch for quickly interrupting the power supply in an emergency. Such arrangements have several disadvantages, however, especially since provision for manual turning of the control forward and backward to shorten or eliminate cycles or to repeat cycles is very desirable. For example, the user may wish to shorten the wash time after the automatic operation has begun or may wish to eliminate entirely one or more rinse periods in machines where several are employed. Moreover, for certain types of laundry loads, it may be desirable to repeat a single rinse operation where only one is automatically provided. For these and other reasons, the provision of means for manually turning the control in either direction is very desirable and should

not be eliminated if other means can be found to overcome the problems encountered in rapid manual switching. Moreover, the provision of a separate "on-off" switch to interrupt the power supply in an emergency is a considerable expense and is made unnecessary when a timing mechanism constructed in accordance with my invention is used.

Another defect of prior controls, of a somewhat different nature, is that with the usual tolerances and ordinary tapering cam surfaces, actuation of the control switches by the cam followers is not always sufficiently exact for the close requirements of the operational sequence. This problem cannot be overcome by the provision of a separate "on-off" switch and a non-reversible control mechanism, while my invention not only makes such an arrangement unnecessary but also provides more accurate switch operation.

Accordingly, it is an object of my invention to provide an improved control for a sequence of operations including provision for adjusting the duration of and eliminating or repeating operations.

It is another object of my invention to provide an improved control incorporating an arrangement for permitting limited manual reversal and including stop means located at a plurality of pause positions.

In carrying out my invention, I provide a program controller having a timer motor driven cam drum for activating a group of control switches in a predetermined order. The cam drum may be manually turned in either direction by a control knob or dial, a portion of which projects outside the casing where it can be manipulated by the operator of the machine. A plurality of positions of one cam on the cam drum are provided with stop means effective to limit manual reversal of the drum but ineffective to prevent turning in its driven direction. These stop means are so located as to coincide with the spaces on the cam periphery which effect de-energization of the motor which drives the washing and extracting mechanisms. They, therefore, constitute temporary "off" positions and provide a means by which the machine user can readily find the pause between operations in order to eliminate or repeat any operation of the automatic cycle.

For a better understanding of my invention, reference may now be had to the accompanying drawings in which Fig. 1 is a perspective view of a portion of an automatic washing machine cabinet incorporating my control; Fig. 2 is a plan view of the control mechanism and dial; Fig. 3 is a sectional elevation view of the control mechanism taken along the lines 3-3 of Fig. 2; Fig. 4 is a sectional plan view of the control mechanism taken along the lines 4-4 of Fig. 3, and Fig. 5 is a detail perspective view of certain parts.

Referring to Fig. 1, there is shown a portion of the clothes washer cabinet 1 in which is mounted a control constructed in accordance with my invention. A portion of a control dial 2 projects through a slot 3 in the front wall of the cabinet 1 to permit manual turning of the control to initiate the sequence of timed operations and also for varying the duration of individual operations or eliminating or repeating such operations. In addition, there is shown projecting from the cabinet a manual switch arm 4 which is movable in a slot 5 marked with

the letters "H" and "W" representing the hot and warm control positions for the incoming water. The manually operated switch arm 4 is a common feature on controls for automatic clothes washers and does not constitute a part of my invention.

Referring now to Figs. 2, 3, and 4, the control includes a switch structure 6 including a plurality of switches, not shown. This switch assembly may be of the general type shown in U. S. Patent 2,481,333, granted September 6, 1949, to Heber L. Newell, and owned by the General Electric Company, assignee of the present invention. A plurality of plug terminals 7 project from the end of the switch structure 6 and are adapted to be received within corresponding receptacles, not shown. A mounting bracket 8 is provided for supporting the control structure and the switch assembly 6 is secured to this bracket by a plurality of screws 9, or other suitable fastening devices. A bushing 10 is secured within an opening in the mounting bracket 8 and serves as a bearing for a shaft 11 journaled therein. This shaft provides a common mounting element for various portions of my control, as will be further explained hereinafter. A control or cam drum 12, including a plurality of adjacent cam disks designated as 13, 14, 15, and 16, respectively, is mounted for rotation about the shaft 11. On the drum 12, I provide a hub 17, also arranged to revolve freely on the shaft 11. While only 4 cam disks are shown, it will be understood that any suitable number may be used according to the complexities of the operational sequence controlled by them. The cam disks 13, 14, 15, and 16 are each provided with a cam follower for actuating the switches included within the switch structure 6 to effect the desired sequential control for the washing machine. A cam follower 18 for cam disk 13 and a cam follower 19 for cam disk 14 are illustrated in Fig. 4. They are provided with arms 20 and 21, respectively, which are pivotally mounted on pintles 22 and 23. The follower for cam disk 15 may also be mounted on pintle 22 and the follower for cam disk 16 may be mounted on the pintle 23.

In order to drive the sequential control a constant speed timer motor 24 is provided and may be attached to the underside of the mounting bracket 8 by a plurality of screws as shown in Fig. 3, or by other suitable attaching means. The motor 24, which is preferably a low speed synchronous clock motor, drives a pinion 25 through a gear reduction mechanism, not shown, contained within an enclosing casing 26. Motion is transmitted by the pinion 25 to the shaft 11 through a gear train 27. Its purpose is to further reduce the driving speed and its construction may be similar to that disclosed in the pending application of Harold A. Jones, Serial No. 33,943, filed June 19, 1948, issued August 26, 1952, as Patent No. 2,608,082, for Automatic Washing Machine Control, and owned by the General Electric Company, assignee of the present invention. The cam drum 12 may be driven at as low a speed as one revolution per hour and as viewed in Fig. 2 the direction of rotation is clockwise. The control dial 2 includes a hub 28 which fits loosely on the hub 17 of the cam drum 12 and is carried along with the drum when the latter is driven by the motor 24, so that the dial 2 at all times shows the position of the cam drum and, consequently, indicates the operation then being performed by the washing machine. The dial 2 is

connected to the cam drum 12 by means of a projection 29 on the upper face of the drum which fits into an aperture 30 formed on the dial so that the cam drum 12 and the dial 2 will rotate together in either direction. As shown in Fig. 2, aperture 30 is somewhat larger in diameter than projection 29 thus providing a lost motion connection between the drum and the dial. Thus, since the dial 2 can be manually manipulated, this keying arrangement provides manual means for rotating the cam drum 12 to vary the duration of any given operation and to eliminate or repeat any operation.

Shaft 11 is connected to control drum 12 by means of a ratchet gear 50 fixed on the upper end of shaft 11 and a pawl 51 pivoted on a pin 52 fixed to and projecting upwardly from the top wall of the drum and cooperating with the teeth of the ratchet gear. The pawl is biased toward engagement with the ratchet gear by a spring 53, one end of which is attached to the pawl and the other end to the dial. With this arrangement when ratchet gear 50 is driven in a clockwise direction by motor 24, the ratchet gear carries along with it drum 12 through the intermediary of pawl 51. When control dial 2 is turned manually in a clockwise direction as viewed in Fig. 2, pawl 51 is carried along with the drum, the pawl sliding over the teeth of ratchet gear 50. To permit of dial 2 being turned manually in a counter-clockwise direction, means is provided whereby turning of the dial causes pawl 51 to be moved from engagement with the teeth of ratchet gear 50. To this end, pawl 51 is provided with a projection 54 which stands in a recess 55 in dial 2. Spring 53 holds projection 54 against the wall 56 of recess 55 and at the same time holds the left hand side of aperture 30 against projection 29 as shown in Fig. 2. When dial 2 is turned manually in a counter-clockwise direction it first moves relatively to drum 12 by reason of the lost motion connection between aperture 30 and projection 29 thus turning pawl 51 in a clockwise direction as viewed in Fig. 2 to cause it to move from engagement with the teeth of ratchet gear 50 after which the right hand side of aperture 30 engages projection 29. Continued movement of dial 2 then turns drum 12.

When the sequential control is to be initiated by turning of the knob 2, it is normally moved in a clockwise direction and the duration of the washing cycle in minutes set by moving the appropriate dial indication in alignment with a mark 31 provided on the casing 1 of the clothes washing machine, as shown in Fig. 1.

On the control on which I have chosen to illustrate my invention, I have shown what is considered to be the basic operational sequence necessary in automatic washing machines, and have provided for periods of main drive motor de-energization of sufficient duration to permit the motor to coast to a stop between operations. In addition to the basic cycle, I have shown a "suds kill" feature to show how easily my invention can be made applicable to a control for a more complicated sequence of operations. The standard control cycle shown includes a wash period followed by a pause period to permit the drive motor to coast to a stop, a spin period for extracting the wash water from the basket, another pause period to permit the drive motor to coast to a stop, a rinse period involving the use of the washing mechanism to agitate the clothes, another pause period to permit the drive motor to coast to a stop, a dry period in which the

basket is again rotated to centrifugally extract water from the clothes, and a final pause period during which the drive motor again coasts to a stop, whereupon the sequence of operations has ended. It is apparent that the control disclosed is best applicable to an automatic washing machine in which a reversible motor is used and a direction-responsive clutching arrangement employed for selectively driving the washing means and the spin basket, though my invention can obviously be applied to a wide variety of control arrangements. While the motor is coasting to a stop the switches actuated by the cam followers reverse the drive motor starting winding connections and effect conventional circuits for actuating the electro-responsive water inlet system and other necessary operations. The effect, consequently, is that whenever cam disk 13 is so positioned as to call for one of the aforementioned pause periods the drive motor circuit is interrupted and then, upon the re-energization of the drive motor, its rotation is opposite so that a spin operation will follow an agitate operation and an agitate operation will follow a spin operation.

In order to eliminate the disadvantages already enumerated for conventional control arrangements, I provide stop means which limit manual rotation of the control drum 12 in a direction contrary to its driven direction so that the drum cannot be backed beyond the nearest pause position of cam disk 13. The control may still be freely rotated forward at the user's will by manipulation of the control dial but upon backward rotation a stop is engaged in the first pause position encountered and the drive motor circuit is thereby de-energized until the cam disk rotates or is rotated forwardly to some other chosen position. Consequently, in an emergency, all the operator needs to do to stop the oscillation of the washing means or the rotation of the spin basket is to turn the control dial in a counterclockwise direction, to the first stop encountered. After the operator has had time to remedy the situation giving rise to the emergency, the dial may then be turned to any desired position or to the final pause or "off" position. Moreover, if it is desired to repeat any cycle while the operation is still in progress, it is only necessary to rotate the dial backwardly to its stop and then because the timer motor will continue driving the control drum, the machine will again go through the operation. If it is desired to shorten or eliminate an operation, this may still be done as on conventional timers by merely rotating the dial in its forward direction.

I have illustrated a presently preferred form of my invention in Fig. 4 in which cam disk 13 and cam follower 18 are shown in detail. The cam disk is being driven in a clockwise direction as viewed in Fig. 4 and the cam follower 18 is shown riding up on the tapered trailing edge of the cam recess 32, which recess represents the final pause or "off" position. The follower 18, pivoted as previously described on the pintle 22, carries an insulated member 33 which bears against a switch blade 34, which is preferably of a resilient material. The blade 34 is kept in contact with the member 33 by means of a spring 35 which resiliently biases it in the direction of the follower 18. I provide a contact 36 on the blade 34 and a blade extension 37 in electrically conducting relation with one of the terminals 7. I further provide a contact 38

on an extension of another of the terminals 7 and positioned for engagement with the contact 36. Whenever the cam follower rides onto the high portion of the periphery of the cam disk 13, the member 33 pushes against switch plate 34 to close the contacts. The contacts 36 and 38 remain in engagement so long as the follower rides on a high portion of the periphery of the cam disk 13 but whenever the follower 18 falls into a recessed portion the spring 35 moves the switch blade 34 overcenter, thereby disengaging the contacts. The respective terminals 7 which are electrically connected to the contacts 36 and 38 are connected to the drive motor energizing circuit so that the circuit is completed whenever contact 36 engages contact 38, and is interrupted upon disengagement of these contacts.

Upon continued clockwise rotation of the cam disk 13 by the timer motor 24, the drive motor will be energized and, because of circuits effected by the switches operated by the followers of cam disks 14, 15 and 16 will operate in the direction necessary to cause oscillation of the clothes washing means within the basket. When rotation has continued until the follower 18 falls over the leading edge of and into another recess 39 in the periphery of the cam disk 13, the first pause period begins. The contact 36 is moved away from contact 38 under the urging of the spring 35. During this first pause period, in the manner previously explained, the starting winding of the drive motor is reversed and, as the follower 18 rides up on the tapered trailing edge of the recess 39, the drive motor is again energized, this time for rotation in the opposite direction so that spinning of the basket takes place.

Adjacent the recess 39 in the periphery of the cam disk 13 is provided a recess 40 which is not necessary in a control for the basic operational sequence of an automatic washer but which is shown to illustrate the ease with which my invention may be employed in more complicated control arrangements. The recess 40 permits the addition of a control feature called a "suds kill." This consists of the provision of a solenoid actuated or other electroresponsive water valve with a nozzle directed to spray cold water into the outer tub of the clothes washer just after centrifugal extraction has begun and some wash water from the clothes basket has been discharged into the outer tub. This cold water spray tends to prevent a building up of suds in the tub which would cause a drag on the spinning basket. Such a suds killing spray may be initiated automatically by any suitable control cam arrangement, such as by the provision of a cam lobe 41 on the control dial 2. A cam follower 42, engageable with the dial, is mounted about the switch structure 6 and constitutes a part of a "suds-kill" switch 43. The switch 43 is supported from a plate 44, attached to the mounting bracket 8 by the screws 9, and comprises switch blades 45 and 46 carrying, respectively, contacts 47 and 48. Upon elevation of the cam follower 42 by the cam lobe 41, the contacts 47 and 48 are closed to actuate the "suds-kill" valve. The resulting spray is accompanied by a momentary interruption of the drive motor circuit so that the whipping action of the basket spinning in the suds already accumulated in the tub can be reduced until the cold water spray has had its effect. As indicated by the shape of the notch-like recess 40,

the interruption of the drive motor circuit is of very short duration and does not permit the spinning basket to coast to a stop. Following this momentary interruption, the cam follower rides up to the tapered trailing edge of the notch 40 and the centrifugal extraction operation is continued.

Spinning of the basket ends when the cam follower 18 falls into a recess 49 in the periphery of the cam disk 13, thereby de-energizing the drive motor for the second pause period. This pause period is of longer duration than the first pause period because of the longer time required for the rapidly spinning and usually heavy basket to coast to a stop. During this interruption, the switches actuated by cam disks 14, 15 and 16 effect the necessary circuits for the rinsing operation, including reversal of the start winding for the drive motor and actuation of the water inlet valves. Consequently, when the cam follower rides out of the recess 49 on its tapered trailing edge to the high portion of the cam disk 13, the drive motor turns in the direction necessary to oscillate the washing means once again to flex the clothes in the rinse water. This rinse operation continues until the cam follower 18, riding on the high portion of the cam disk 13, falls into a recess 50, whereupon the drive motor is again de-energized and the third pause period begins. During this pause, the switches actuated by the cam disks 14, 15 and 16 effect the necessary starting winding connection reversal so that when the follower 18 rides up on the tapered trailing edge of the recess 50 to the high portion of the cam disk periphery and causes re-engagement of the contacts 36 and 38, the drive motor will turn in its spin basket driving direction to centrifugally extract the rinse water from the basket.

The entire cycle of operations ends when the cam follower again reaches the recess 32 in the periphery of the cam disk 13, which de-energizes the drive motor for its final pause or "off" period.

To serve as stop means to prevent unlimited reversal of the cam disk 13, as well as to provide sharper and more accurate operation of the drive motor switch, I provide leading edges for the recesses 32, 39, 49 and 50, each of which lies in a plane passing through the axis of the shaft 11. Instead of being severely tapered to permit the cam follower to readily ride up the respective surfaces, as in the case of the trailing edges, the leading edge of each recess is formed at an angle of substantially 90 degrees with the base of the recess so that upon attempted rotation of the cam drum contrary to its driven rotation, the cam follower 18 will engage the leading edge of the first recess of cam disk 13 into which it falls and prevent any further rotation of the cam drum 12 and the dial 2. Of course, any other suitable stop means may be provided at these recesses operable to prevent the cam follower 18 from riding out of a recess when the cam is rotated in a counterclockwise direction, but the provision of substantially right angle leading edges for the cam disk recesses is simple, economical and effective and in addition provides sharper and more accurate switch opening than does the usual sloping surface. By changing the shape of the forward edge of the cam follower 18, moreover, a widely varying angle for the leading edges of the cam disk recesses can be successfully used.

It would not be desirable in an emergency for the operator to turn the cam disk 13 so that the

follower 18 engages the suds kill recess 40, as the initiation of the suds spray would be disconcerting and the power interruption would be of too short a duration. In view of this, both the leading and trailing edges of the notch which forms recess 40 have been severely tapered so that the follower 18 will easily ride out of the suds kill recess, no matter in which direction the cam is rotated. Consequently, the only stop positions provided coincide with those recesses in which the drive motor is de-energized for a true pause and for a sufficient time to permit the driven mechanism to coast to a complete stop. As a result, my stop means provides excellent emergency "off" positions, since the drive motor will be de-energized for a sufficient period of time for the operator to overcome any initial bewilderment and turn the dial to its final pause or "off" position. The operator may readily determine the location of this position by turning the dial in its forward direction past the "off" marking and then backing it up until it reaches the "off" position stop. This eliminates the guess-work involved in turning most controls to the "off" position and makes it unnecessary for the operator to carefully listen for the snapping of switches or other indications that the machine is fully deenergized.

While I have shown a particular embodiment of my invention, it will be understood, of course, that I do not wish to be limited thereto, since many modifications may be made; and I, therefore, contemplate by the appended claims to cover any such modifications as fall within the true spirit and scope of my invention.

What I claim as new and desire to secure by Letters Patent of the United States is:

1. A controller for a motor-driven apparatus comprising a timer motor, a cam disk having a peripheral face on which are provided alternate raised and recessed portions, clutch means connecting the timer motor to said cam disk and through which it drives a cam disk, said clutch means being releasable to permit turning of the cam disk in either direction independently of said timer motor, a follower for said cam disk, a switch operable upon movement of said cam follower to one of said raised portions to complete a drive motor circuit and operable upon movement of said cam follower to one of said recessed portions to interrupt said drive motor circuit, manual means connected to said cam disk for turning it in a direction contrary to its driven direction, and stop means located at the leading ends of selected circuit interrupting recesses which engage with said follower to prevent turning of said cam disk in said contrary direction beyond the leading edge of a selected recess.

2. A controller for a motor-driven apparatus comprising a timer motor, a cam disk having a peripheral edge on which are provided alternate raised and recessed portions, clutch means connecting the timer motor to said cam disk and through which it drives the cam disk, said clutch means being releasable to permit turning of the cam disk in either direction independently of said timer motor, a follower for said cam disk,

a switch operable upon movement of said cam follower to one of said raised portions to complete a drive motor circuit and operable upon movement of said cam follower to one of said recessed portions to interrupt said drive motor circuit, and manual means connected to said cam disk for turning it in a direction contrary to its driven direction, at least some of said recessed portions having abrupt leading edges shaped to engage said follower upon contrary rotation of said cam disk to prevent turning of said cam disk in said contrary direction beyond the leading edge of the recessed portion.

3. For use in a clothes washing machine having a rotatable basket with oscillatable washing means disposed therein and a drive motor for alternately driving said basket and said washing means, a controller comprising a timer motor, a control drum, clutch means through which the timer motor drives the control drum for effecting a series of operations including the oscillation of said washing means, the rotation of said basket, a drive motor de-energization period between each said oscillating and rotating operation, and a final drive motor de-energization following the last such operation, said clutch means permitting the control drum to be turned in a direction opposite to its driven direction independently of said timer motor, manual means connected to said control drum for turning it in a direction opposite to its driven direction, stop means at the leading ends of selected drive motor de-energization positions, and stop means carried by said drum which engage said first named stop means upon such manual turning to limit the movement of said control drum.

4. A controller for a motor-driven apparatus comprising a timer motor, a cam disk having alternate raised and recessed portions, clutch means through which the timer motor drives the cam disk, said clutch means permitting the cam disk to be turned in a direction opposite to its driven direction independently of said timer motor, a follower for said cam disk, a switch operable upon movement of said cam follower to one of said raised portions to complete a drive motor circuit and operable upon movement of said cam follower to one of said recessed portions to interrupt said drive motor circuit, said recessed portions being provided with gradually sloping wall portions to permit said follower to readily ride up on said raised portion upon normal rotation of said cam, at least one of said recesses being provided with a leading wall portion shaped to engage the edge of said follower to prevent said follower from riding up on said raised portion upon reverse rotation of said cam disk, and manual means for turning said cam disk in the reverse direction from its normal driven direction.
